Primary Examiner — Janice Seeger*(74) Attorney, Agent, or Firm* — Sughrue Mion, PLLC(57) **CLAIM**

The ornamental design for a table with monitor stand, as shown and described.

DESCRIPTION

FIG. 1 is a perspective view from the front side of a table with monitor stand.

FIG. 2 is a perspective view from the rear side thereof.

FIG. 3 is a front elevation view thereof. A rear elevation view is a mirror image of the front elevation view.

FIG. 4 is a right side elevation view thereof.

FIG. 5 is a left side elevation view thereof.

FIG. 6 is a top plan view thereof.

FIG. 7 is a bottom plan view thereof.

FIG. 8 is an enlarged cross-sectional view taken along the line 8-8 in FIG. 4.

FIG. 9 is an enlarged cross-sectional view taken along the line 9-9 in FIG. 3.

FIG. 10 is an enlarged cross-sectional view taken along the line 10-10 in FIG. 3; and,

FIG. 11 is a referential view showing use thereof.

The portion shown in broken lines in FIG. 11 is for the purpose of showing environmental structure only and forms no part of the claimed design.
